CLAIM

The ornamental design for a golf club, as shown and described.

DESCRIPTION

FIG. 1 is a top, left, and rear isometric view of an ornamental design for a golf club;

FIG. 2 is a rear elevational view of the golf club of FIG. 1; FIG. 3 is a front elevational view of the golf club of FIG. 1; FIG. 4 is a right side elevational view of the golf club of FIG. 1;

FIG. 5 is a left side elevational view of the golf club of FIG. 1;

FIG. 6 is a top plan view of the golf club of FIG. 1; FIG. 7 is a bottom plan view of the golf club of FIG. 1; and, FIG. 8 is a top, right, and front isometric view of the golf club of FIG. 1 coupled with a golf club shaft to form a golf club.

The dash-dash-dash broken lines illustrate portions of the golf club that form no part of the claimed design. The dash-dot-dash broken lines illustrate boundary lines and form no part of the claimed design.
